Des. 214,821
Patented July 29, 1969

214,821

HARD SURFACE FLOOR COVERING OR SIMILAR ARTICLE

Alfredo A. Franco, Lancaster, Pa., assignor to Armstrong
Cork Company, Lancaster, Pa., a corporation of Pennsylvania

Filed Feb. 20, 1967, Ser. No. 5,864

Term of patent 14 years

Int. Cl. D5—05

U.S. Cl. D92—4

The figure is a plan view of a hard surface floor covering embodying my new design, with a design unit being enclosed within the horizontal and vertical dash-dot lines, which unit is repeated in regular succession as indicated by the extensions beyond the unit boundaries.

I claim:

The ornamental design for a hard surface floor covering or similar article, substantially as shown and described.
